UNITED STATES PATENT OFFICE.

JOHN H. WALBRIDGE AND JOHN P. STEPP, OF BROOKLYN, ASSIGNEES TO
HAFF & WALBRIDGE, OF NEW YORK, N. Y.

HAIR CURLER AND FRIZZER.

SPECIFICATION forming part of Letters Patent No. 423,972, dated March 25, 1890.

Application filed October 10, 1889. Serial No. 326,637. (No model.)

To all whom it may concern:

Be it known that we, JOHN H. WALBRIDGE and JOHN P. STEPP, both of Brooklyn, in Kings county, and State of New York, have 5 invented a certain new and useful Improvement in Hair Curlers and Frizzers, of which the following is a specification.

This improvement relates to devices such as are used by ladies for curling and frizzing 10 their hair.

Our improvement consists in the combination of a tube, a rod or bar movable out of the tube for heating and into the tube to transmit heat to the latter, and a clasp or finger serving 15 to grasp and hold hair around the tube.

In the accompanying drawings, Figure 1 is a side view of a hair-curler embodying our improvement. Fig. 2 is a similar view with certain of the parts in a different position.

20 Fig. 3 is a transverse section, on a larger scale, taken at the plane of the dotted line *x*, Fig. 1.

Similar letters of reference designate corresponding parts in all the figures.

25 *A* designates a tube, (here shown as of cylindric form.) It may be made of any suitable metal and finished in any desirable manner. This tube is provided with a hand-piece *B*, which will preferably be made of 30 some material which is a poor conductor of heat. For instance, it may be made of wood.

35 *C* designates a clasp or finger, (here shown as consisting of a strip which is straight longitudinally, but concave or convex transversely.) At one end it is pivoted by a pin *f* to the tube *A*, so that at the outer end it may be swung away from the tube or toward it, and when swung toward it it will be adapted to fit an adjacent portion of the tube 40 snugly. As here shown there is formed with the clasp or finger an arm *C'*, which with the clasp or finger forms a lever. On this arm *C'* is a hand-piece *c* of insulating material. By pressing upon this hand-piece *c* the outer 45 end of the clasp or finger may be swung away from the tube. A spring *D* serves to force the clasp or finger toward the tube. In the present instance the spring *D* is fastened to the arm *C'* and impinges against the tube *A*.

50 *E* designates a rod or bar fitted within the

tube *A* and movable outwardly beyond the same. It is shown as having a hand-piece *e*, whereby it may be adjusted longitudinally. The shank of this hand-piece extends through a longitudinal slot *a* in the tube *A*. The rod 55 or bar *E* may therefore be moved lengthwise of the tube *A* to project it beyond the same or withdraw it into the same; but it does not extend into the handle. There may be a spring between the hand-piece *e* and the tube 60 to exert sufficient friction upon the tube to retain the rod or bar in any position into which it may be adjusted. We have shown a sheet-metal spring *F* for this purpose. It consists of a concave or convex strip of sheet 65 metal bearing upon the outside of the tube *A*. The shank of the hand-piece *e* passes through it, and the inner end of the body of the hand-piece bears against it and holds it against the tube *A*. 70

When this curling or frizzing device is to be used, the rod or bar *E* is moved outward from the tube *A*, and may then be heated by any suitable flame or fire. When heated, it will be withdrawn into the tube *A*. Heat will 75 be transmitted from it to the tube *A* sufficiently for curling or frizzing the hair. The clasp or finger *C* will be swung outwardly and the hair to be curled or frizzed placed between it and the tube, whereupon the clasp 80 or finger will be moved or allowed to move inwardly to grasp and hold the hair between it and the tube. Afterward the curler or frizzer may be twisted to wind the hair upon the tube and hold it there until sufficiently heated to 85 remain in curl.

The movable rod or bar is very advantageous. It may be subjected to any heat, and yet will not dirty the hair, because it will be withdrawn into the tube, and the latter only 90 will come in contact with the hair. Moreover, it is advantageous because the tube coming in contact with the hair is less liable to become unduly heated when it is heated through an independent rod or bar than if 95 directly heated.

What we claim as our invention, and desire to secure by Letters Patent, is—

1. In a hair curler or frizzer, the combination of a tube, a handle therefor, a rod or bar 100

movable out of the tube for heating it and into the tube for heating the tube, said rod or bar not movable into the handle, a clasp or finger pivoted to the tube, and a spring, 5 substantially as specified.

2. In a hair curler or frizzer, the combination of a tube, a rod or bar movable out of and into the tube, a slot in the tube, a hand-piece extending through the slot in the tube 10 to the rod or bar, a friction-spring between the hand-piece and tube, a clasp or finger pivot-

ally connected to the tube, and a spring, substantially as specified.

JOHN H. WALBRIDGE.
JNO. P. STEPP.
